Des. 239,593

Patented Apr. 20, 1976

239,593

MOUNTING CLIP OR THE LIKE

William L. Douma, West Paterson, N.J., assignor to Thomas & Betts Corporation, Elizabeth, N.J.

Filed Mar. 14, 1975, Ser. No. 558,312

Term of patent 14 years

Int. Cl. D8—08

U.S. Cl. D8—233

FIG. 1

FIG. 2

FIG. 3

FIG. 4FIG. 5*FIG. 6

FIG. 1 is a front perspective view of a mounting clip or the like, showing my new design;

FIG. 2 is a front elevational view thereof;

FIG. 3 is a top plan view thereof;

FIG. 4 is a right elevational view, the left being a mirror image of the right;

FIG. 5 is a rear elevational view thereof; and

FIG. 6 is a bottom plan view.

I claim:

The ornamental design for a mounting clip or the like, substantially as shown and described.
